UNITED STATES PATENT OFFICE.

ISAAC P. WALDEN, OF ST. LOUIS, MISSOURI.

DESIGN FOR A WAGON-BODY.

SPECIFICATION forming part of Design No. 17,276, dated April 19, 1887.

Application filed February 3, 1887. Serial No. 226,486. Term of patent 7 years.

To all whom it may concern:

Be it known that I, ISAAC P. WALDEN, a subject of the Queen of Great Britain, and residing at St. Louis, Missouri, have invented a new and useful and original Design for Wagon-Bodies, and produced the same, of which the following is a specification, reference being had to the accompanying drawing, forming a part thereof.

10 The figure in the drawing is a perspective view of my wagon-body mounted on an ordinary truck or running-gear.

The leading feature of my design consists in the sides and ends of the body of long parallel 15 lateral panels and ribs or raised surfaces running along the sides and ends of the body. These panels are formed by constructing parallel lateral ribs or raised surfaces *a a a a* on the sides and ends of the body. The ribs or 20 raised surfaces *a a a a* are placed sufficiently far apart to make panels *b b* between them. Thus these ribs and panels, running clear around the body laterally and parallel to each other, present to the eye a wagon-body appearing to 25 be in lateral sections, when in fact it is in one piece. The lower rib, *a*, extends across the front end of the wagon in an unbroken line, as shown, and this rib, upon the side, extends

to within a short distance of the wheel *c*, where it curves upward and forms the circle *d* over 30 the top of the wheel. The upper portion of the wheel extends up into the box *e*, as shown.

I know there have been wagon-bodies having lateral sections, and also wagon-bodies with panels and raised surfaces on the side and end 35 thereof; but they do not have the raised surfaces running clear around the body, as mine does; neither do the panels run clear around the body, as mine does, but are divided by perpendicular raised surfaces connecting the 40 lateral raised surfaces, and thus destroys the effect which my lateral raised surfaces and panels produce.

Now, what I claim, and for which I ask Letters Patent to be granted, is—

The design for a wagon-body herein shown and described, the same consisting of the raised portions or ribs *a*, running laterally around the sides and ends of the wagon-body and forming panels *b*, and the curved rib *d*, which extends around the outer end of the box *e* over 50 the top of the wheel *c*, as shown.

ISAAC P. WALDEN.
